UNITED STATES PATENT OFFICE.

BENJAMIN I. HULIN, OF CAMBRIDGE, ILLINOIS.

FASTENING FOR WAGON-BOXES.

SPECIFICATION forming part of Letters Patent No. 248,751, dated October 25, 1881.

Application filed April 23, 1881. (No model.)

To all whom it may concern:

Be it known that I, BENJAMIN I. HULIN, a citizen of the United States, a resident of Cambridge, in the county of Henry and State of Illinois, have invented a new and valuable Improvement in Fastenings for Wagon-Boxes; and I do hereby declare that the following is a full, clear, and exact description of the construction and operation of the same, reference being had to the annexed drawing, making a part of this specification, and to the letters and figures of reference marked thereon.

The figure of the drawing is a representation of the device in use.

This invention has relation to means for securing the upper box of a wagon-body to the lower or permanent box, in order to prevent the opening of the joint and the consequent loss of grain; and the invention consists in the construction and novel arrangement of the curved and weighted hook on the top box or board, and the eye plate or brace on the lower box, all as hereinafter described and claimed.

In the accompanying drawing, the letter A designates the lower or permanent box of the wagon, having the plate or brace B, provided at its upper end with an eye, c.

D represents the upper or removable box or box-board, having the cleats E, or other support, for holding it upright on the lower box.

G indicates the curved hook. This is pivoted by its middle portion to the upper board, D, and is provided with a weighted arm, h, which is arranged on the opposite side of the

35 pivot k from the hook-branch l, but forming an angle therewith, as indicated in the draw-

ing. This hook is pivoted near one of the cleats E, or near a stop, its distance horizontally from the same being less than the length of the arm h, so that when the hook is disengaged from the eye c and thrown upward said arm will come in contact with the cleat or stop, and, being sufficiently weighted, will hold the hook-branch up so that it will remain in position above the lower margin of the upper board, 45 D, and will not be liable to injury in the removal of said board from the box A.

When the upper box is in position and it is desired to use this fastening the hook is thrown forward or backward, as the case may be, and descending with some degree of force, because of the weighted arm, its beak b enters the eye c, and is automatically held in engagement therewith by the arm or handle h, the weight of which is now transferred to the opposite 55 side of the pivot k.

Having described this invention, what I claim, and desire to secure by Letters Patent, is—

In a wagon-fastening for connecting the upper and lower box, the curved hook G, whereof the weighted arm h and hook-branch l form an angle with each other, as shown, the stop or cleat E, and the eye-brace or eye-plate, substantially as specified.

In testimony that I claim the above I have hereunto subscribed my name in the presence of two witnesses.

BENJAMIN I. HULIN.
